OSCILLATOR

Oran T. McIlvaine, St. Charles, Ill.

Application February 16, 1935, Serial No. 6,812

2 Claims. (Cl. 250—27.5)

My invention relates to the control of electric currents, and includes among its objects and advantages an improvement in control means particularly useful in connection with the transformation of direct current to alternating current.

In the accompanying drawing:

Figure 1 is a partly diagrammatic cross section of an oscillator according to the invention on line 1—1 of Figure 2;

Figure 2 is a section on line 2—2 of Figure 1;

Figure 3 is a diagram of a circuit employing the oscillator of Figures 1 and 2;

Figure 4 is a diagram of another circuit employing the same oscillator; and

Figure 5 is an enlarged detail showing a heated electrode.

In the embodiment of the invention selected for illustration, the oscillator comprises an evacuated bulb 10 provided with a plurality of terminals indicated at 12, 14, and 16 passing through the press 18. The terminals 12 and 16 have duplicate contact portions 20 and 22 lying on opposite sides of the central contact 24. The contact 24 is connected to the conductor 14 by a leaf spring 26 weighted at its outer end as by a weight 28.

30 is an actuating coil for the weight 28, which weight is of magnetic material. For most frequencies the coil 30 may be provided with a core 32.

34 indicates the capsule containing the emitter. I have secured good results with caesium for the emitter, in which case the capsule may be a mechanical mixture of metallic calcium and caesium 35 chloride. Discharge of the capsule results in the formation of calcium chloride and metallic caesium in excess of that necessary to provide a caesium atmosphere inside the bulb. I have obtained good results with caesium when the clearance between the contacts 20 and 22 is such that when the contact 24 is against one of them, the space between the contact 24 and the other is of the order of magnitude of .006 inch.

In Figure 3 I have indicated wiring for converting the direct current generated by the battery 36 into an oscillating current delivered from the secondary winding 38 of the transformer 40 and suitable for the operation of an alternating current radio receiving set. The midpoint of the 50 primary 42 is connected to the positive terminal of the battery 36, and the negative terminal is connected directly through the conductor 14 to the cathode 24. The anode 22 is connected to one end of the primary at 44, and the anode 20 is connected to the other end at 46. The coil 30 is

interposed in series with the anode 20. I have indicated a condenser 48 bridging the contacts 24 and 22, and a condenser 50 bridging the contacts 24 and 20.

The arrangement of Figure 4 is identical except that, to secure more perfect symmetry of movement, I employ two actuating coils. The coil 52 is connected in parallel with the contacts 22 and 24, and the coil 54 is connected in parallel with the contacts 20 and 24.

With this arrangement one of the coils is always pulling the weight 28 in the direction of the contact with which the cathode 24 is not engaged, and the actuating impulses and the movement of the weight will be completely symmetrical. I have also indicated a single condenser 56 bridged across contacts 20 and 22 to steady the current flow.

In Figure 5 I have indicated a construction identical with that of Figure 1 except that the cathode 58 extends a little at 60, and the extension lies inside a small heating coil 62 whereby the temperature of the cathode may be raised.

With the clearances and emitter specified I have been able to convert direct into alternating current with a direct current input of 30 watts and an output of 28 watts. As the losses thus measured include the hysteresis loss in the transformer and the di-electric losses in the entire system, it is obvious that the energy wasted at 30 the contacts is extremely small. Another fact evidencing the high efficiency of the contacts as such is that such a set can operate for long periods without warming the bulb enough so that its warmth can be noticed, whereas a very small wattage is adequate to raise the temperature of such a bulb until it becomes distinctly warm to the hand.

Without stating that such is the case, I believe the explanation of the facts above recited to be 40 that the caesium atmosphere accomplishes a material contamination of the contact surfaces with a layer of caesium that may or may not build up to a thickness of one molecule over the entire surface.

This surface of caesium, or in large part caesium, is well known to have a very low work function, and even at room temperatures there is a material emission of electrons, most of which, in the absence of a steep potential gradient to accomplish their withdrawal, describe an orbit and return to the contact surface in which they originated. The presence of such an emissive contact surface has two material effects on the operation of the system as a whole. First, when 55

the contacts are in mechanical engagement, the microscopic and sub-microscopic clearances between most of the surfaces in ordinary mechanical contact are permeated with the electrons emitted and this greatly decreases the contact resistance. Second, as the cathode 24 moves away from one anode, the current flow is not chopped off with the abruptness that would occur in the absence of an emitter, but is reduced gradually during the removal of the cathode to a distance from the anode equal to the mean effective orbit of the electrons. Similarly, as the cathode completes its traverse and approaches the other anode, the current flow between the cathode and the other anode is initiated materially in advance of mechanical contact and built up gradually.

If this theory is correct, the net result is that the effective forces tending to generate the oscillatory flux in the transformer are not imposed and discontinued abruptly in step by step fashion, but become effective in accordance with a curve that will be a much closer approximation to a sine curve. This would contribute greatly, not only to the smoothness of the oscillator current issuing from the winding 38, but to the ease with which a condenser of suitable size can be made to tune the different parts of the circuit so that mechanical separation between the cathode and each anode occurs at a time when the relatively high frequency disturbance of the current flow caused by such separation will be a minimum.

Without further elaboration, the foregoing will so fully explain my invention that others may, by applying knowledge current at the time of such application, readily adapt the same for use under various conditions of service. It will, for instance, be obvious that any one of a number of other emitters might be employed and that one or more of the contacts 20, 22, and 24 may be heated to a greater or less degree to build up the

emissivity of the contact surfaces to the extent found most advantageous; also that other substances such as inert gases at suitable pressures may be included in the filling for the bulb for various purposes.

5

I claim:

1. An oscillator comprising, in combination: a sealed bulb; a pair of spaced contacts therein; a third contact between said spaced contacts; means for oscillating said third contact between said spaced contacts; and an emitter in said tube, wherewith the contact surfaces are contaminated, said emitter being capable of emitting electrons at room temperature; the clearance between said contacts permitting said third contact a range of movement greater than, but of the same order of magnitude as, the mean effective orbit for an electron originating in the surface of the cathode at room temperatures and under the potential gradients obtaining during normal operation.

10

2. An oscillator comprising, in combination: a sealed bulb; a pair of spaced contacts therein; a third contact between said spaced contacts; means for oscillating said third contact between said spaced contacts; and an emitter in said tube, wherewith the contact surfaces are contaminated; the clearance between said spaced contacts permitting said third contact a range of movement of the order of magnitude of the distance through which the electronic emission from the cathode influences the effective resistance to current flow between said contacts; said oscillating means including a weight and a resilient connection between said weight and said third contact, permitting said weight an excursion extending in both directions beyond the positions corresponding to engagement between said third contact and one of said pair of contacts.
